UNITED STATES PATENT OFFICE.

GUSTAVE E. KASCHUB, OF MERIDEN, CONNECTICUT.

OUTLET BOX AND PLATE THEREFOR.

Application filed March 16, 1923. Serial No. 625,482.

To all whom it may concern:

Be it known that I, GUSTAVE E. KASCHUB, a citizen of the United States, residing at Meriden, in the county of New Haven and State of Connecticut, have invented a new and useful Improvement in Outlet Boxes and Plates Therefor; and I do hereby declare the following, when taken in connection with the accompanying drawings and the characters of reference marked thereon, to be a full, clear, and exact description of the same, and which said drawings constitute part of this application, and represent, in—

15 Fig. 1 a side view, partly in section, of an outlet-box and plate therefor, constructed in accordance with my invention.

Fig. 2 an inside view of the face-plate detached.

20 Fig. 3 a face view of the outlet-box with the plate removed.

Fig. 4 a broken view, in vertical section, illustrating the engagement of the face-plate with the outlet-box.

25 Fig. 5 a face view of a face-plate adapted for plug connections.

This invention relates to improvement in outlet-boxes and plates therefor, and particularly in outlet boxes as arranged in side-walls and with which wall brackets are connected. The object of this invention is to provide an outlet-box with which a plate may be detachably connected, which plate may carry an electrical mounting of any desired form, and which may be interchanged one for the other, and the invention consists in the construction as hereinafter described and particularly recited in the claims.

40 In carrying out my invention, I employ an outlet-box 10, of any approved form, as herein shown, being provided with lugs 11, by which it may be secured in place, and also provided with screw-holes 12, by which it may be secured in position, according to where the box is located. This box is provided with the usual clearance-opening 13 for circuit-wires 14 and 15, which lead to binding-screws 16 and 17 in electrical connection with contact-plates 18 and 19, which are mounted in a block 20 of insulating material located in the box between inclined guideways 21 and 22 formed integral with

the box and at the bottom of which are sockets 23 and 24 for the purpose as will 55 hereinafter appear. The block 20 rests upon a longitudinally-corrugated plate 25 of spring metal mounted in the bottom of the box, so as to form a yielding bearing for the block 20 against inward pressure, 60 and this plate is formed, at its lower end, with a spring-finger 26 against which the block may be downwardly moved. This block is removably secured in place by means of a bolt 27, which extends through 65 a clearance-slot 28 formed for it in the inner wall of the box and the spring plate 25, the slot in the box being narrower than the diameter of the nut applied to the outer end of the bolt. A wall plate 29 may also be 70 of any approved design, and mounting two inclined pins 30 and 31 adapted, respectively, to engage with the guides 21 and 22 and be thereby guided into the sockets 23 and 24, whereby the plate is firmly secured 75 in position. This plate also mounts a block 32 of insulating material having contact surfaces 33 and 34 arranged to engage with the contacts 18 and 19, these contacts being connected by wires 35 and 36 to a lamp-socket 37 mounted on an arm 38 secured 80 in the face-plate. Instead of the lamp-socket and arm, the face-plate may be provided with a plug-receiving member 39, with which a plug of usual construction may be 85 connected when it is desired to electrically connect a vacuum cleaner, a cooking utensil, or other electrical appliance. Or, in case it is desired to use a plain plate to cover an outlet-box where no electrical connection 90 is to be made, this plate may be a blank plate provided with pins 30 and 31, by which it may be connected with the outlet box. When used for any other than ornamental purposes, the plate may consist 95 merely of a strip sufficient in extent to mount the pins 30 and 31 and the block 32. As the face-plate is moved downward, into position, the inclination of the pins draws it against the wall, so as to make a close 100 fit therewith, and the spring-plate 25 and the spring-finger 26 provide for yielding movement of the block 20 to insure proper electrical contact with the block 32.

I thus provide, in a very simple way, an 105 outlet box with which a fixture of any de-

sired type may be connected, the fixture itself being completely wired, so that it may be removed and replaced by another fixture when desired.

5. I claim:

1. The combination with an outlet box formed on opposite sides with integral, inclined guideways, and with sockets at the lower ends thereof, of a contact-block arranged between the said guideways, and a face-plate provided with inclined pins adapted to enter the said sockets.

10. 2. The combination with an outlet box formed on opposite sides with integral, inclined guideways, and with sockets at the lower ends thereof, of a contact-block yieldingly mounted between the said guideways, and a face-plate provided with inclined pins adapted to enter the said sockets.

15. 3. The combination with an outlet box formed on opposite sides with integral, inclined guideways, and with sockets at the

lower ends thereof, of a contact-block arranged between the said guideways, contact-plates mounted in said block, a face-plate, a block of insulating material secured to the face-plate, contacts mounted in the block in the face-plate, complementary to the contacts in the box, the said face-plate provided with inclined pins adapted to enter the said sockets.

20. 4. The combination with an outlet-box formed on opposite sides with integral inclined guideways, and with sockets at the lower ends thereof, of a contact-block arranged between said guideways, a spring between said block and box, whereby the block is yieldingly supported against inward pressure, and a face-plate provided with inclined pins adapted to enter said sockets.

25. 35. 40. In testimony whereof, I have signed this specification.

GUSTAVE E. KASCHUB.
